BELT COMPOSED OF LONGITUDINAL SEPARATED BANDS

Application filed November 21, 1928, Serial No. 321,003, and in Belgium November 30, 1927.

The invention relates to belts composed of longitudinal separated bands and its object is to devise such belts superior to those known hitherto in many respects.

The known belts of this kind composed of longitudinal separated bands are held together by means of transverse straps. The present invention devises a belt of this kind, with longitudinal bands composed of two, 10 three or four layers of leather, balata or tissue and so on, connected between them in the transverse direction by means of thin, flexible straps of leather, preferably parchment leather, or spring steel, these straps being inserted between the different layers of the bands and fixed (by simple nails in case of leather and by riveting for steel) only to the outer longitudinal bands, the purpose of such construction being to leave free play to 20 the inner layers of the belt, adhering to the pulley, and, furthermore, to dissimulate the heads of the nails or rivets.

The different layers constituting the longitudinal bands are connected between them in 25 the sense of depth by forked rivets placed between the cross-straps in such manner that the belt passing over the pulley is permitted to bend around the ranges of rivets, forming so as to say hinges. The rivets placed between the cross-straps, are countersunk with 30 regard to the surface frictioning on the pulley, so as to avoid all contact with the latter.

The drawings appended illustrate in the 35 way of example, as an embodiment of the invention, a belt composed of two superposed layers of leather bands.

Fig. 1 shows a part of such belt in plan view;

Fig. 2 is a cross-section according to line 40 2—2 of Fig. 1;

Fig. 3 is a longitudinal section according to line 3—3 of Fig. 1.

The longitudinal bands of about 15 to 20 45 cm. of width are, according to the shown embodiment, formed by the superposition of two

layers of leather, viz. the inner layer *a* and the outer layer *b*, preferably of the same degree of extensibility in order to permit an integral power-transmission. The layers of leather are of course of appropriate quality 50 according to the kind of work and ensure a perfect adherence of the belt to the pulley.

The longitudinal bands are connected between them in the cross-sense by straps of about 12 to 25 mm. of width, appropriate to the diameter of the pulley and thin and flexible and at the same time having a certain rigidity necessary at the moment of uncoupling the pulley. In order to obtain this effect, it was thought preferable to employ 55 for straps a parchment leather or leather dried in raw state, which material is very well apt for work demanding continuous bending. The appropriate thickness of the straps will be about 1 mm. to 2,5 mm. Eventually instead of leather straps galvanized 60 spring steel may be employed, more especially for belts working in wet spots, the thickness of steel being only 4/10 to 10/10 mm. 65

The cross-straps are inserted between the layers *a* and *b* and are fixed only to the longitudinal outer bands *b*, by nailing or riveting *d*, (according as to whether the material employed for these straps is leather or steel), 70 so as to ensure free play of the layer *a* applied to the pulley and to dissimulate at the same time the heads of the nails or rivets *d* by the layers *a*. 75

The arrangement of the cross-straps between the different layers constituting the longitudinal bands procures to the belt the fixidity and rigidity of the straps; this is not the case with the straps placed outwardly, according to some belts of this kind 80 executed hitherto.

The different layers *a*, *b* constituting the longitudinal bands are connected to each other by forked rivets *d* placed between the cross-straps *c* (Fig. 1) in order to permit 85 90

the flexion of the belt and to counter-sink the rivets by their bent points e_1 with regard to the surface frictioning on the pulley, so as to avoid contact with the rivets.

5 The depressions formed by the lower layers a are exaggerated in Fig. 3, so as to illustrate the counter-sunk position of the rivets and the impossibility to deteriorate the pulley and also, the formation of small suction recesses f increasing the adherence of the belt to the pulley.

10 At the spots of these recesses, the leather is acted upon only by suction and not by the rivets e and do not rub on the pulley, except where the intercalated cross-straps c of steel pass.

15 The straps c of steel avoid weakening of the layer a , the whole effort being taken up by the rigid and flexible cross-straps and the leather acting only as a kind of mattress. Consequently the leather does not undergo any effort whatsoever, where the longitudinal and cross bands are crossing each other.

20 The elongation of the belt is nearly zero and always by far smaller than the one of the belts hitherto used.

25 Theoretically, the distance between two neighboring cross-straps c ought not to surpass 12 mm. for double belts, and 18 to 22 mm. for fourfold belts, in order to permit squeezing of the straps at both sides by riveting of the bands, a , b , the straps being permitted thereby to transmit the lateral force at the moment of clutching without any deformation of the belt.

30 It must be noted that the layers a , b being separated, the maximum of adherence is obtained owing to the lateral flexibility; the layers a , b can consist of leather of the same kind, and even of very soft leather; the lateral rigidity exists at the same time as the flexibility and this result is obtained by drawing nearer the straps c , so as to fix them rigidly by riveting together the layers a , b .

35 The invention is of course not limited to the embodiment represented permitting quite a scope of modifications, with regard to the number of the elements constituting the belt, the material employed, the manner of assembling these elements and so on.

40 What I claim, is:

45 1. A power transmission belt composed of inner sinuous longitudinal members, outer longitudinal members secured to said inner longitudinal members at points corresponding to the convex portions of said inner members so that the intermediate curved portions of the inner members are spaced from the outer members, and transverse connecting members arranged in the spaces between said inner and outer members and secured to the latter at points substantially intermediate those at which the inner and outer members are secured together.

50 2. A transmission belt as claimed in claim

1, in which the outer longitudinal members are non-sinuous and the transverse connecting members are flat.

55 3. A transmission belt as claimed in claim 1, in which the inner and outer longitudinal members are secured together by fork rivets.

60 In witness whereof I affix my signature.
